UNITED STATES PATENT OFFICE.

EDWARD V. BODDY, OF ARTESIA, NEW MEXICO.

COIN-CONTROLLED MECHANISM FOR VENDING-MACHINES AND THE LIKE.

1,139,477.

Specification of Letters Patent. Patented May 18, 1915.

Application filed May 28, 1914. Serial No. 841,631.

To all whom it may concern:

Be it known that I, EDWARD V. BODDY, a citizen of the United States, residing at Artesia, in the county of Eddy and State of New Mexico, have invented certain new and useful Improvements in Coin-Controlled Mechanism for Vending-Machines and the like; and I do declare the following to be a full, clear, and exact description of the invention, such as will enable others skilled in the art to which it appertains to make and use the same.

My invention relates to improvements in vending machines and more particularly to those which are primarily designed for dispensing cards, envelopes, periodicals and the like.

The primary object of the invention is to provide a device of this character which may be simply and inexpensively constructed and which will effectually perform the functions for which it is designed.

In carrying out the above end, I provide a casing, feeding mechanism therein for dispensing the cards, operating means for said feeding mechanism, and coin tripped means for normally locking said operating means against movement.

A secondary object of the invention is to construct said coin tripped means in such a manner as to allow the coin to be readily discharged therefrom as the operating mechanism is actuated.

A further object of the invention is to construct the feeding mechanism of a single piece of wire formed into a coil and having one end contracted for the purpose of providing a support for said coil.

A still further object of the invention is to construct the entire device in the most simple manner consistent with its effective operation.

With these objects in view, the invention resides in certain novel features of construction and combination herein described and claimed and shown in the drawings wherein:—

Figure 1 is a front elevation of a vending machine constructed in accordance with my invention, showing the manner in which warning is given when the machine is empty; Fig. 2 is a top plan view of the machine with the cover raised and showing more particularly the construction and positioning of the feeding coil; Fig. 3 is a vertical transverse section taken along the

plane of the line 3—3 of Fig. 2 showing the positioning of parts before a coin is inserted; Fig. 4 is a similar view showing the manner in which the locking mechanism is released by the insertion of a coin; Fig. 5 is a view similar to Figs. 3 and 4 and illustrating more particularly the manner in which the coin receptacle is tilted by the actuation of said operating means; Fig. 6 is a transverse section taken along the plane of the line 6—6 of Fig. 5; Fig. 7 is a detail vertical section taken on the line 7—7 of Fig. 3, showing more particularly the means for preventing retrograde movement of the operating shaft; Fig. 8 is a perspective view of the coin receptacle; Fig. 9 is a detail vertical section showing the manner in which the feeding coil is supported upon its shaft; and Fig. 10 is an enlarged side elevation of the locking lever and coin receptacle thereon.

In the accompanying drawings, I have shown but one unit of my improved vending machine, it being understood that the structure illustrated therein may be duplicated a number of times in the same machine, thus allowing the latter to be adaptable for the disposition of various articles.

Each unit comprises a rectangular casing 1 which is provided with a removable coin drawer 2 in its lower end, the upper portion 3 of the front 4 of said casing being preferably formed of a glass panel 5 behind which the article to be vended may be displayed. As most clearly seen in Figs. 1 and 3 the panel 5 is spaced outwardly from the lower section 6 of the front, thus providing a slot 7 which extends transversely across the device and through which the vended articles are discharged.

Seated within the lower portion of the casing 1, is a central bearing support 8 which carries, on its rear side, a bearing plate 9, the latter extending above said support 8 and forming a journal for a stub shaft 10, the latter carrying, on its outer end, a spur gear 11 while its inner end forms a rotatable support for the feeding coil 12 above mentioned. For the purpose of more rigidly supporting the shaft 10, I preferably extend its outer end beyond the gear 11 and revolubly mount the same in a suitable bearing carried by the rear side of the casing.

The above mentioned feeding coil is formed of a single piece of wire bent to form the convolutions of said coil and hav-

ing its rear end contracted as indicated at 13, said contracted portion surrounding the inner end of the stub shaft 10 and having its outermost convolution bent inwardly 5 and seated within a notch 14 formed in said shaft. By this construction and positioning of parts, it will be readily seen that when said laterally turned portion is sprung outwardly from its engagement with the 10 notch 14, the entire coil may be removed from the stub shaft, this becoming expedient in order that coils of various pitches may be applied since, as will be understood, a coil whose convolutions are closely 15 spaced would not operate to advantage for the purpose of supporting rather thick articles, it being understood that said articles, indicated at A, are disposed between the convolutions of the coil and supported 20 thereby.

From the parts so far described, it will be readily seen that since the forward end of the coil 12 projects over the slot 7, rotation of said coil will feed the articles A 25 forwardly until they are dropped one by one through said slot.

As simple and efficient means for rotating said coil, I have provided an operating shaft 15 which has its forward end revolution- 30 bly mounted through the lower portion of the front of the casing while its rear end is mounted in a suitable bearing 16 carried by the rear of the casing, its intermediate portion being further supported in an aper- 35 ture formed in a laterally extending ear 17, the latter being carried by the bearing plate 9. The outer end of the shaft 15 is provided with any suitable operating handle 18 by means of which said shaft may be rotated when a locking means, to be described, is released by the insertion of a coin. The motion thus imparted to said shaft 15 is transferred to the spur gear 11 through an idle gear 19 and a gear 19' carried by 40 the shaft 15 thereby rotating the shafts 15 and 10 in the same direction. As most clearly seen in Fig. 7, retrograde movement on the part of the shaft 15 is prevented by 45 a pawl and ratchet mechanism, the ratchet 50 20 thereof being carried by the shaft 15 while the pawl 21 is pivoted to the bearing plate 9 and normally pressed against said ratchet by means of a suitable spring.

By reference to the various figures of the 55 drawings, it will be seen that the spur gear 19' and the ratchet 20 are spaced upon the shaft and that a radially extending arm 22 is interposed between the two, said arm having a portion which is passed through 60 the shaft 15 and upset or riveted, thus caus- 65 ing said arm to rotate with the shaft. Since it becomes necessary for the ratchet 20 and the gear 19 to rotate simultaneously with the shaft 15 and the arm 22 and for the sake of obviating the use of unnecessary

keys for the purpose of securing said gear and ratchet upon the shaft, I have provided a pair of fastening screws 23 which pass through the ratchet, on opposite sides of the arm 22 and enter said gear 19'. Thus it 70 will be seen that any motion on the part of the gear and ratchet is prevented unless said arm is allowed to rotate. The arm 22 is not only provided for the purpose of locking the gear 19' and the ratchet 20 75 against rotation in respect to the shaft 15, but constitutes a portion of a coin tripped latch mechanism for preventing rotation of said shaft 15 and thereby the rotation of the coil 12. For this purpose, the arm 80 projects a considerable distance beyond the periphery of the ratchet wheel 20 and is provided with a forwardly extending stud 24 the latter being adapted to engage the rear end 25 of a latch lever 26, the latter being 85 pivoted intermediate its ends as indicated at 27 and having its forward portion reduced as indicated at 28 for the purpose of lightening this end of the lever in order that the rear end thereof may fall by gravity 90 into the path of the stud 24, said lever having its pivot disposed nearer to its front end than to its rear end to assist its movement as above set forth. Said reduced portion 28 of the lever 26 is provided, on its 95 extreme front end, with a bearing stud 29 which is provided at its inner and outer ends with stop collars 30 and 31 respectively.

Pivottally swung beneath the lever 26 and 100 beneath an appropriate coin chute 32, is a coin receiving member or receptacle 33, the latter being here shown as formed of a single piece of wire bent to form a horizontal ring 34 into which the coin is adapted 105 to drop. The wire extends upwardly and forwardly after forming said ring and is given a number of coils around the stud 29 as indicated at 35, its free end extending laterally as indicated at 36 and constituting 110 a trip arm by means of which the ring 34 may be tilted for the purpose of discharging a coin therefrom.

For the purpose of tilting said ring 34 at the proper time, I have provided the shaft 115 15 with a radially extending trip arm 37 which, like the arm 22, has a longitudinally extending stud 38, said stud being adapted to engage the under side of said trip arm 36, as the shaft 15 is rotated, thereby tilting 120 the same as clearly illustrated in Figs. 5 and 6. It may here be explained that the weight of the rear end of the lever 26 is greater than the combined weights of the forward end thereof and the receptacle 33 125 and the downward movement of said rear end is limited by a suitable stop 39 which is preferably carried by the bearing support. Thus it will be seen that the loop or ring 34 is at all times correctly positioned 130

beneath the chute 32 and that when a coin is inserted in said chute, the weight thereof will overbalance the rear end of the lever 26 thus allowing the same to rise out of the 5 path of the stud 24, this allowing the shaft 15 to be rotated by its handle 18 throughout one revolution. During this revolution of the shaft 15, the feeding coil 12 is rotated one revolution through the before described 10 gearing and one article is forced forwardly by said coil and allowed to fall through the slot 7. This rotation of the shaft 15 also causes the trip stud 38 to contact with the trip arm 36 to tilt the ring 34, thereby dis- 15 charging the coin into the drawer 2, and again allowing the rear end of the lever 26 to drop into the path of the stud 24 thereby preventing further rotation of the above mentioned parts.

20 It will thus be seen that the insertion of a coin trips the locking means and allows the operating means to be actuated and that the movement of said operating means actuates the feed mechanism and also tilts the coin 25 receptacle allowing the parts to again be locked at the end of a revolution.

The above described operation may be repeated successively until all of the cards have been discharged from the machine, at 30 which time a card or plate 40 bearing the word "empty" will fall through the slot 7, the downward movement of said card being limited by a pair of rearwardly extending stops 41 which contact with the upper edge 35 of the lower half of the front of the casing.

From the foregoing description, taken in connection with the accompanying drawings, it will be seen that I have produced a comparatively simple device for carrying 40 out the objects of the invention and one which may be inexpensively manufactured.

I have described my invention with considerable minuteness but I do not wish to be limited to details of construction other than 45 those amplified in the appended claims.

Having thus described my invention, what

I claim as new and desire to secure by Letters Patent is:—

1. In a device of the character described, an operating shaft, a radially extending 50 locking arm on said shaft and having an inwardly extending stud at its free end, a trip arm likewise extending radially from said shaft, a lever pivoted intermediate its ends beneath said shaft and having one of 55 its ends overbalanced and located in the rotary path of said stud, a stop for preventing excessive downward movement of said overbalanced end of the lever, a pivot stud formed on the opposite end of 60 said lever, a substantially upright wire having its intermediate portion formed into a pivot coil surrounding said pivot stud, the upper end of said wire constituting a trip arm and being located in the rotary path 65 of the trip arm on said shaft, and a coin receiving ring formed integrally with the lower end of said wire and designed to receive a coin whereby to raise the overbalanced end of said lever out of the path of 70 the first mentioned stud.

2. In a device of the character described, an operating shaft, locking means therefor, a depressible lever for releasing said locking means, said lever being located beneath 75 the shaft and having one end provided with a pivot stud, a substantially upright wire arm having its intermediate portion loosely coiled around said stud, the lower end of said arm being bent to form a horizontal 80 coin receiving ring, a coin chute above said ring, and a trip arm on the shaft and designed to contact with the upper end of said substantially upright wire arm when said shaft is rotated.

In testimony whereof I have hereunto set my hand in presence of two subscribing witnesses.

EDWARD V. BODDY.
